JOHN B. HADAWAY, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

CUTTING-MACHINE.

1,389,654.

Specification of Letters Patent. Patented Sept. 6, 1921.

Application filed April 29, 1918. Serial No. 231,349.

To all whom it may concern:

Be it known that I, JOHN B. HADAWAY, a citizen of the United States, residing at Swampscott, in the county of Essex and State of Massachusetts, have invented certain Improvements in Cutting-Machines, of which the following description, in connection with the accompanying drawings, is a specification, like reference characters on the drawings indicating like parts in the several figures.

This invention relates to cutting machines and particularly to machines for cutting blanks from sheet material by the use of freely movable dies.

In a well-known type of cutting machine in which a crosshead and a cutting block are mounted for relative movement toward and from each other, the crosshead, in all positions thereof, is arranged in close juxtaposition to the cutting block, the result being that the machine is adapted for operation only on materials having uniform characteristics throughout. In operating on sheet materials presenting qualities which vary in different portions of each sheet, it becomes a matter of importance that the operative should have sufficient light to permit of thorough inspection of the material and space to enable him to adjust the die in accordance with his judgment as to the proper location thereof.

It is an object of the present invention to provide an improved construction in which the cutting bed and the means for exerting pressure on a die located on material on the cutting bed shall be so related that sufficient light and space may be obtained to locate the die most advantageously upon material having variable characteristics, and in which means is provided for insuring effective operation of the pressure applying means so that the die is caused invariably to effect a dieing-out operation on the work.

In the preferred form of the invention a crosshead and a cutting bed or block are mounted for relative movement toward and from each other and a presser member is provided as the immediate means for applying pressure to the die on the material, the construction being such that the presser

member is co-extensive with a very considerable portion of the cutting block so that no careful or painstaking adjustment of the presser member with respect to the die is necessary preliminary to the cutting operation which takes place during the relative movement of the crosshead and cutting block.

In a practical form of the invention, the crosshead is mounted for movement toward and from the cutting block, the presser member being arranged to move with the crosshead to effect the forcing of the die through material on the cutting block. Preferably the presser member is pivoted on the crosshead adjacent to one end thereof and is movable laterally relatively thereto to admit of the die being placed upon material on the cutting block under the most favorable conditions as to space and light.

Among other features of importance may be mentioned the provision of a plurality of presser members arranged to be operated by the crosshead, the construction and arrangement being such that a die may be operated upon by both presser members simultaneously, or either presser member may be caused to apply singly an operative stroke to a die properly positioned with respect thereto. Preferably electrical means are provided for causing instantaneously the application of power to the crosshead to operate either or both of the presser members. Inasmuch as this application of power is attained at a very minimum of effort on the part of the operative, the arrangement described adds greatly to the efficiency of both operative and machine. In a practical form of the invention a switch, in an electrical circuit comprised in the electrical means referred to above, is mounted upon each of the presser members in a location readily accessible to the operative for controlling the application of power to the machine.

Other features of novelty which contribute to the carrying out of objects of the invention hereinbefore enumerated, or of other objects of the invention which will be apparent from a consideration of the disclosure of the invention in the specification and

drawings, will be pointed out in the following detailed description and included in the claims.

In the accompanying drawings,
5 Figure 1 is a front view of one embodiment of the cutting machine;

Fig. 2 is a sectional view taken along the line 2—2, Fig. 1;

10 Fig. 3 is a detail view showing a solenoid in connection with the starting treadle;

Fig. 4 is a section along the line 4—4 in Fig. 2, the said section extending into a part of the crosshead to show the means for holding the presser member, in adjusted position 15 with respect to the crosshead; and

Fig. 5 is a section through the solenoid shown in Fig. 3.

In the illustrative machine, the reference character 6 designates the frame of the machine upon which is mounted a member 8 20 which serves as a support for the cutting block 10. Preferably, the support 8 is slidably mounted in the frame so that it may be adjusted vertically to raise or lower the cutting block, the adjustment being effected 25 through screw threaded members operated in the usual way through hand wheels 12.

Mounted in the frame 6 is the main shaft 14 carrying the loose-pulley 16 which may 30 be clutched thereto by means of any well-known type of a one-revolution non-repeating clutch partly disclosed at 18. Extending upwardly from yokes movably attached to eccentrics, one at each end of the main shaft, are pitmen 20, connected in pairs between the yokes and the ends of the crosshead 22, the arrangement being such that one revolution of the main shaft 14 causes 35 a complete reciprocation of the crosshead in 40 a direction toward and from the cutting block 10. Located between the crosshead 22 and the cutting block 10 are presser members 24, the same being mounted preferably on the crosshead, by means of posts 26 to move 45 with the crosshead in its reciprocations. In order to assist in guiding the presser members during their reciprocations and in order 50 to prevent any tendency to distortion when pressure is applied to dies on the work the posts 26 are guided in passageways 28 in the member 8. The cutting bed may be completely uncovered to enable the operative to place the die most advantageously upon the material to be cut, the presser members 24 55 being mounted so that they may be displaced to one side. Preferably this movement is provided for by mounting the posts 26 rotatably in both the crosshead 22 and the member 8. Extending upwardly from the body 60 portion of each pressure member and also from the extremity thereof is a plurality of posts or extensions 30, the said extensions being connected in pairs at their upper ends by crossbars 32, said crossbars being connected in turn by a plate 34 extending longitudi- 65

nally of the under surface of the crosshead 22. The construction thus described has the purpose of transmitting pressure from crosshead 22 to the presser members evenly at a plurality of points in each presser member. 70 An important feature of the machine shown and described resides in the provision of means, here embodied in a crosshead construction, for forcing the presser member down onto the die constructed to apply sufficient pressure to the presser member to accomplish the cutting of a blank or blanks at each operation of the machine with the greatest regularity. The presser member is so mounted and operated that any tendency 75 to distortion of the presser member itself or of its supporting parts, under the great strains imposed during the operation of the machine, is taken care of most efficiently. This is a matter of importance in any type 80 of cutting machine but particularly so in the present construction wherein the presser member is mounted for movement laterally of the cutting block to uncover the same during positioning of the die or dies. It will be 85 noted that each extension is adjustably connected at its lower end to the presser member and at its upper end to the crossbars 32, the arrangement being such that cross bars 32 and connecting bar 34 may be so adjusted as to bring their combined upper surfaces into a position just short of contact with the crosshead 22 when the latter is in its uppermost position. In order to provide 90 for holding the presser member in proper relation to the crosshead during the reciprocations thereof, a spring pressed locking means 95 36 is mounted in one of the crossbars 32 in such a position that it may coöperate selectively with any one of a plurality of openings 38 in the under surface of crosshead 22. It will be understood, however, that any other form of holding means than that shown might be employed to secure the 100 presser member in proper relation to the 105 crosshead. 110

Heretofore it has been the custom in cutting machines of the type to provide a treadle mechanism for tripping the clutch when it was desired to throw the machine 115 into operation. This mechanism has been retained in the present embodiment of the invention and is disclosed in Figs. 1 and 3 of the drawings, wherein said mechanism is shown as consisting of levers 40 secured to 120 a crossbar 42 extending through the frame of the machine, the two outside levers each having attached thereto a rod 44 connected by a bell crank 45 to a link 47 for operating the clutch mechanism through the connections shown. The treadle, comprising a tread portion 51 which extends across and is securely attached to the treadle levers 40, is normally held in its upward position by means of a spring 46 connected with a 125 130

treadle at its forward end and to a crossbar on the machine frame. An important feature of the invention consists in the provision of electrical means for operating the treadle, the same consisting of a commercial form of solenoid 48 attached to the middle treadle lever 40 and at its upper end to a stationary extension 50 of the machine frame. Passage of a current through the 5 solenoid results in a downward movement of the rod 49 (Fig. 5) and hence of the treadle lever 40 with the resultant shifting of the clutch to cause one revolution of the main shaft. The device 48 is in two electrical circuits consisting in part of wires 52 which lead to a source of electrical energy not shown, each circuit containing a switch located at a point readily accessible to the operative. In the present embodiment of 10 the invention each switch 54 is located upon one of the presser members. Thus in the operation of the machine the crosshead may be caused to descend to drive a die through the material on the cutting block through 15 the interposition of one or both presser members 24 upon the proper manipulation of one of the switches 54. Should the operative be placing the die upon material at the right of the cutting block in Fig. 1, he will 20 of course use the switch located upon the presser member at the right of the machine. If both the presser members are being used to operate upon a plurality of dies, or upon one die located under the adjacent ends of 25 the presser members, both presser members will be caused to descend simultaneously upon proper manipulation of either switch. Control of the operation of the presser member in a cutting machine by electrical means 30 is claimed broadly in the co-pending application of J. B. Hadaway, Serial No. 207,869, filed Dec. 19, 1917.

The manner of operation of the machine will be obvious from the facts set forth in 45 the above detailed description of the parts of the machine. However, the manner of cutting out blanks from sheet material may be briefly set forth as follows: With the presser members 24 positioned laterally out 50 of the way in positions indicated by dotted lines in Fig. 2 of the drawings, a sheet of material is placed upon the cutting block 10. It is obvious that with the presser members so located sufficient light is permitted access to inspect the material as to its various 55 qualities in order to decide upon the proper location of the die and to place the die in accordance with the location decided upon.

Another feature of importance in this construction and arrangement is found in the 60 fact that the operative may manipulate the material and the die with absolute safety to himself while the presser member is at one side of the cutting bed. When the die 65 has been properly positioned, the presser

member is returned to operative position over the die by means of a handle 55 provided for that purpose, and the machine is then operated at the will of the operative. If the die be located at the center part of 70 the longitudinal dimension of the cutting bed, both presser members will be drawn forwardly in position over the die and automatically locked in such position. If a plurality of dies are placed upon the cutting 75 bed so that one or more of the dies is under each presser member both presser members will be brought into operative position. On the other hand, if but one die is used at a time and that properly located with respect 80 to one of the presser members, the other presser member may be left in inoperative position. In any case, operation of the machine can be most easily and quickly initiated simply by manipulation of one of the 85 switches 54 on the presser members.

Having described my invention, what I claim as new and desire to secure by Letters Patent of the United States is:—

1. In a machine of the class described, a cutting block and a crosshead relatively movable toward and from each other, and a presser member co-extensive with approximately one-half of the cutting block and mounted for movement from and into position over the block between said block and crosshead. 90

2. In a machine of the class described, a cutting block and a crosshead relatively reciprocable toward and from each other, and a presser member arranged for movement to a fixed position relative to the cutting block for co-operation invariably with a certain predetermined portion of the cutting block during cutting operations and mounted for 100 reciprocatory movements in different directions along paths angularly related to each other. 105

3. In a machine of the class described, a cutting block and a crosshead relatively reciprocable toward and from each other, a presser member mounted to swing into and out of position between the block and crosshead, and positive means for holding the presser member in operative position. 110

4. In a machine of the class described, a cutting block, a frame for supporting said block, a crosshead reciprocable toward and from the block, a presser member movable from and into position between the block 120 and crosshead, and a support for said member operatively connected to said frame and to said crosshead.

5. In a machine of the class described, a cutting block, a crosshead reciprocable toward and from the block, and a presser member co-extensive with approximately one-half of the cutting block and pivoted on the crosshead and movable therewith. 125

6. In a machine of the class described, a 130

- cutting block, a crosshead reciprocable toward and from the block, and a presser member arranged to sustain a fixed relation to the cutting block for coöperation invariably with the same portion of the cutting block and mounted for reciprocatory movements in both horizontal and vertical planes in functioning in coöperation with the block and crosshead.
10. 7. In a machine of the class described, a cutting block and a crosshead relatively movable toward and from each other, a presser member mounted for movement independent of the crosshead from and into position over the block and constructed and arranged to be given an operative movement by the cross head when in position over the block, and means for determining the operative position of the presser member with respect to the block.
8. In a machine of the class described, a cutting block, a crosshead reciprocable toward and from the cutting block, and a presser member operated invariably from approximately one-half of the under surface of the crosshead, the arrangement being such that pressure is applied from the crosshead to the presser member throughout substantially the entire area of the latter, whereby distortion or displacement of the presser member about any horizontal axis while under pressure is prevented.
9. In a machine of the class described, a cutting block, a crosshead reciprocable toward and from the cutting block, a presser member, and means for locking the presser member in various positions with relation to the crosshead.
10. In a machine of the class described, a cutting block, a crosshead reciprocable toward and from the cutting block, a presser member, and means for locking the presser member automatically as it arrives in parallel relation with the crosshead.
45. 11. In a machine of the class described, a cutting block, a crosshead reciprocable toward and from the block, and a presser member having a surface extending over the greater part of the length of the presser member from its point of support for engagement with the under surface of the crosshead.
55. 12. In a machine of the class described, a cutting block, a crosshead reciprocable toward and from the block, and a presser member having an upward extension above its free end, said extension having a surface arranged to engage with the under surface of the crosshead, the construction and arrangement being such that the presser member has pressure applied thereto from approximately one-half of the presser surface of the crosshead.
60. 13. In a machine of the class described, a cutting block, a crosshead reciprocable to-

ward and from the block, and a presser member spaced from the crosshead and having upward extensions carrying a crossbar arranged to engage the under surface of the crosshead.

14. In a machine of the class described, a cutting block, a crosshead reciprocable toward and from the block, and a presser member having upward extensions carrying a crossbar arranged to engage the under surface of the crosshead, said crossbar and crosshead being provided with coöperating means to retain the presser member fixedly in operative position.

15. In a machine for cutting blanks from sheets of material by means of freely movable dies, a cutting block and a crosshead relatively movable toward and from each other, and a presser member co-extensive with approximately one-half of the cutting block, movable laterally of the crosshead and operative during relative movement of the crosshead and block toward each other for forcing the die through sheet material on the cutting block.

16. In a machine for cutting blanks from sheets of material by means of freely movable dies, a cutting block and a crosshead relatively movable toward and from each other, and a presser member mounted on a pivot extending across the ends of the crosshead and cutting block, movable from and into operative position between the crosshead and block and operable during relative movement of the crosshead and block toward each other for forcing the die through sheet material on the cutting block.

17. In a machine for cutting blanks from sheets of material by means of freely movable dies, a cutting block, a crosshead reciprocable toward and from said block, and a presser member pivotally mounted on said crosshead at one extremity of the longitudinal axis thereof for reciprocation therewith and operable to force a die through sheet material on the cutting block.

18. In a machine for cutting blanks from sheets of material by means of freely movable dies, a cutting block and a crosshead relatively movable toward and from each other, and a plurality of presser members presenting presser surfaces together substantially coextensive with the surface of the cutting block and operative either selectively or together during relative movement of the crosshead and block toward each other for forcing the die or dies through sheet material on the cutting block.

19. In a machine for cutting blanks from sheets of material by means of freely movable dies, a cutting block and a crosshead relatively movable toward and from each other, and a plurality of presser members mounted so that each may be moved out of and into operative position and presenting

- when all are in operative position a presser surface substantially coextensive with the surface of the cutting block and operative to force a die or dies through sheet material
- 5 on the cutting block when relative movement of cutting block and crosshead takes place.
20. In a machine for cutting blanks from sheets of material by means of freely movable dies, a cutting block, a crosshead movable toward and from said block, and a plurality of presser members mounted to move with the crosshead and so arranged as to be capable of coöperation as the crosshead descends in forcing a single die through sheet material on the block.
- 10 21. In a machine for cutting blanks from sheets of material by means of freely movable dies, a cutting block, a crosshead movable toward and from said block, and a plurality of presser members constructed and arranged to be operated simultaneously as the crosshead descends to apply pressure to a die located opposite portions of more than one presser member.
- 25 22. In a machine for cutting blanks from sheets of material by means of freely movable dies, a cutting block and a crosshead relatively movable toward and from each other, a pair of presser members mounted so that operative movement of one or both of the presser members takes place upon relative movement of crosshead and block, and electrical means comprising switches mounted one on each presser member for controlling the operation of the machine.
- 30 23. In a machine for cutting blanks from sheets of material by means of freely movable dies, a cutting block and a crosshead relatively movable toward and from each other, a pair of presser members mounted so that operative movement of one or both of the presser members takes place upon relative movement of crosshead and block, and electrical controlling means comprising switches mounted one on each presser member.
- 35 24. In a machine for cutting blanks from sheets of material by means of freely movable dies, a cutting block, a crosshead movable toward and from the block, a pair of presser members mounted to move with the crosshead, power means including a one-revolution clutch for causing reciprocations of the crosshead, a lever for controlling said clutch, and electrical means comprising a solenoid for operating said lever and a switch mounted in a position accessible to the operative for controlling said clutch.
- 40 25. In a machine for cutting blanks from sheets of material by means of freely movable dies, a cutting block, a crosshead movable toward and from the block, presser members arranged to be operated upon movement of the crosshead toward the cutting block, and electrical means comprising
- a switch mounted upon each presser member for controlling the operation of the machine, said means and switches being constructed and arranged to provide for either conjoint and simultaneous or independent operation 70 of the presser members at the will of the operator.
26. In a machine for cutting blanks from sheets of material by means of freely movable dies, a cutting block and a crosshead relatively movable toward and from each other, power means for causing relative movement of crosshead and block, a presser member operative during relative movement of the crosshead and block for forcing a die or dies through sheet material on the cutting block, a treadle lever for controlling said power means, and an electrical means comprising a solenoid for operating said lever and a switch mounted on the presser member for controlling the operation of the power means.
- 75 27. In a machine for cutting blanks from sheets of material by means of freely movable dies, a cutting block and a crosshead relatively movable toward and from each other, power means comprising a one-revolution clutch for causing relative movements of crosshead and block, presser members movable out of and into position to coöperate with the cutting block and crosshead during relative movement of the latter to force a die or dies through sheet material on the cutting block, and electrical means comprising switches mounted one on each 80 presser member for controlling the operation of the clutch.
- 90 28. In a machine of the class described, a cutting block, a presser member mounted for movement laterally of the block and also for reciprocation toward and from the block, a frame for supporting the cutting block and presser member, and means comprising a cross-head having a surface arranged to apply pressure on the presser member for causing said reciprocation of the presser member, the pressure receiving and pressure applying surfaces on the presser member approximating closely in size to the pressure applying surface on the crosshead, whereby great pressure may be applied on a die located on the cutting block without danger of distortion of the presser member and its supporting frame.
- 95 29. In a machine of the class described, a cutting block and a crosshead relatively movable from and toward each other, a presser member co-extensive with approximately one-half of the cutting block and arranged for movement from and into position between said crosshead and block, the construction and arrangement being such that the presser member may be displaced from its operative position to permit of the die being positioned on the material with 100
- 105 110 115 120 125 130

absolute safety to the operative after which the presser member may be returned to operative position over the die, and means for causing the operation of the machine at the 5 will of the operative.

30. In a machine of the class described, a work supporting bed, a plurality of presser members having together a pressure surface substantially coextensive with the surface of 10 the bed, and means for operating a plurality of the presser members simultaneously.

31. In a machine of the class described, a work supporting bed, a plurality of presser members supported above said bed and arranged in close juxtaposition to each other, and means for operating a plurality of the 15 presser members simultaneously.

32. In a machine of the class described, a work supporting bed, a plurality of presser members supported above said bed and movable into and out of operative relation with 20 respect to the bed, a crosshead having one of said presser members supported adjacent to each end thereof, and means for causing 25 a pressure applying operation of a presser member.

33. In a machine of the character described, a work supporting bed, a plurality of presser members supported above the bed for operation upon work located on the bed, 30 and a single means for simultaneously operating a plurality of the presser members.

34. In a machine of the character described, a work supporting bed, a plurality of presser members having together a pressure surface substantially co-extensive with the surface of the bed, power means for operating the presser members, and a single means for initiating simultaneously the 35 operation of a plurality of the presser members.

35. In a machine of the class described, a cutting block, a crosshead reciprocable toward and from the block, and a presser member arranged to move into position between the crosshead and the cutting block to cover invariably the same predetermined portion of the cutting block to coöperate therewith during cutting operations.

In testimony whereof I have signed my 50 name to this specification.

JOHN B. HADAWAY.
